(57) **CLAIM**

We claim the ornamental design for an imaging system patient gantry and patient bed, as shown and described.

DESCRIPTION

FIG. 1 is rear, top, right side perspective view of an imaging system gantry and patient bed with the bed rotated to a patient ingress/egress position, showing our new design;

FIG. 2 is a rear, top, right side perspective view of the imaging system gantry and patient bed with the bed partially rotated toward an imaging position;

FIG. 3 is a rear, top, right side perspective view of the imaging system gantry and patient bed with the bed in an imaging position;

FIG. 4 is a rear side elevational view of the imaging system gantry and patient bed with the bed in an imaging position;

FIG. 5 is a front side elevational view of the imaging system gantry and patient bed with the bed in an imaging position

FIG. 6 is a left side elevational view of the imaging system gantry and patient bed with the bed in an imaging position; and,

FIG. 7 is a front, right, top side perspective view of the imaging system gantry and patient bed with the bed in an imaging position.
